(57) **CLAIM**

The ornamental design for a retractable cord housing, as shown and described.

DESCRIPTION

FIG. 1 is a perspective view of a retractable cord housing showing our new design with rubberized texturing on the handle shown in broken lines;

FIG. 2 is a top plan view thereof;

FIG. 3 is a side elevational view looking from the bottom of FIG. 2;

FIG. 4 is a side elevational view looking from the right side of FIG. 2;

FIG. 5 is a side elevational view looking from the left side of FIG. 2;

FIG. 6 is a side elevational view looking from the top of FIG. 2; and,

FIG. 7 is a bottom plan view of the FIG. 1 housing with cord lengths extending from the housing added and shown in broken lines.

The elements shown in broken lines in FIGS. 1, 2 and 7 are illustrating environment only and form no part of the claimed design.
